United States Patent Office.

GEORGE W. LARGE, OF YELLOW SPRINGS, OHIO.

Letters Patent No. 61,744, dated February 5, 1867.

IMPROVED GATE LATCH.

The Schedule referred to in these Letters Patent and making part of the same.

TO WHOM IT MAY CONCERN:

Be it known that I, GEORGE W. LARGE, of Yellow Springs, Greene county, Ohio, have invented a new and useful Gate Latch; and I do hereby declare the following to be a full, clear, and exact description thereof, reference being had to the accompanying drawings, making part of this specification.

This invention relates to a form of latch for gates and doors, which latch, in the act of closing, becomes available as a lever to slightly elevate the free end of the gate, and thus to correct any tendency to sagging.

Figure 1 is a perspective view of a gate provided with the "lever latch," the gate being unlatched.

Figure 2 is a perspective view of a portion thereof, the gate being latched.

A represents a customary farm or door-yard gate, hung to a post, B, and closing against a post, C. D is a catch, of usual form. The latch proper, E, instead of dropping into the catch D by its gravity, has its pivot F so placed as to cause the portion 1, most distant from the catch, to preponderate so as to gravitate reversely from the usual direction, and to elevate the outer end 2 of the latch, as seen in fig. 1. The portion 1 of the latch is made limber, so as to press snugly against a catch, G, whose shoulder g receives and retains the latch when the latter is lifted on to the same. The gravitating portion 1 of the latch may have any convenient handle, H, and may be restricted in its play by a yoke, I. The gate being closed, but unlatched, as in fig. 1, the portion 1 of the latch is elevated so as to bring the portion 2 to bear upon the catch D as on a fulcrum, thus converting the latch into a lever of the second kind, by whose instrumentality the free end of the gate is lifted bodily upward, the limberness of the portion 1 enabling it to ascend the incline g' of the catch G, and to snap or engage over the shoulder g of said catch. The latch, thus resting by its two ends on the catches D and G, and being pivoted to the free end of the gate, effectually preserves the latter from sagging. In the act of unlatching, the limberness of the portion 1 becomes again available, by enabling the dislodgment of the latch from the shoulder g. The latch and catches may be of metal or of hard wood.

I do not propose to restrict myself to the precise form selected for illustration, as the same may be modified; for example, the latch may be rigid and the catch G yielding; and a spring may co-operate with or replace the gravitation of the latch, and the part 1 may form an angle with the part 2.

I claim herein as new, and of my invention—

The reversely gravitating lever latch, constructed and operating substantially as and for the purpose set forth. In testimony of which invention I hereunto set my hand.

GEO. W. LARGE.
